UNITED STATES PATENT OFFICE.

ERIK W. SETTERLUND, OF SANDRIDGE, MANITOBA, CANADA.

SAW-SET.

1,096,131.

Specification of Letters Patent.

Patented May 12, 1914.

Application filed July 7, 1913. Serial No. 777,662.

To all whom it may concern:

Be it known that I, ERIK W. SETTERLUND, a citizen of Canada, residing at Sandridge, in the Province of Manitoba, in the Dominion of Canada, have invented certain new and useful Improvements in Saw-Sets, of which the following is a specification.

This invention relates to improvements in saw sets and its object is to produce a device 10 of this class that is easily applied and operated and which may be quickly and accurately adjusted to teeth of various sizes and degrees of pitch.

With the foregoing and other objects in view the invention consists in the combination and arrangement of parts to be herein-after fully described in the following specification, pointed out in the claim and illustrated in the accompanying drawing which 20 forms a part of said specification and in which—

Figure 1 is a side elevation of my improved saw set. Fig. 2 is a plan view of the same. Fig. 3 is a longitudinal section in 25 side elevation. Fig. 4 is a section taken on line 4—4 of Fig. 3.

Like reference characters indicate corresponding parts throughout the several views.

30 My saw set comprises an upper jaw 1 which comprises an integral sheath 2 and a head 3. To the jaw 1 the lower jaw formed with a handle section 4 and a head section 5 is secured by a pivot 6 and a pin 7 which 35 passes through an elongated slot 8 in the sheath 2. The lower jaw sections 4, 5 are flexibly connected as at 9 by a pin 10. About the aforesaid pin 6 passes a spring 11, the extremities of which rest against the handle 40 portions of the upper and lower jaws to force the same apart as best shown in Fig. 3. 12 is a saddle passing about the sheath 2 and engaging the ends of the pin 7 and said saddle is provided with a set screw 13 by 45 means of which the distance between the two jaws and hence the pressure of the one jaw upon the other through the spring 11 may be regulated.

14 is a bifurcated guide plate mounted 50 upon the head 3 of the jaw 1 and provided with a set screw 15 in its bifurcated portion

which screw passes through the said head and through the medium of which the said guide plate may be adjusted longitudinally of said head. The forked terminations 16, 55 17 of the guide plate are disposed upon opposite sides of the head 3 normally in the plane of the apertured portion 18 of said head which portion is disposed in alinement with the apertured portion 19 of the lower 60 jaw which portion opens into an elongated apertured portion 20 in said jaw in which the thumb nut 21 is disposed that carries and actuates the anvil 22 that extends up through the apertured portion 19 of the lower jaw 65 to engage the teeth of the saw blade 23 under operation.

Operation: The saw blade 23 is passed between the upper and lower jaws at their forward termination after the guide plate 70 14 has been adjusted upon the head 3 to regulate the distance that the said blade shall extend into the tool. The jacket 12 is adjusted to regulate the tension of the upper and lower jaws, the thumb nut 21 is then 75 rotated to the right or left to raise or lower the anvil as desired depending upon the degree of pitch to be given the tooth, the jaws are then manually pressed together and the operation is performed upon one tooth; the 80 operation is, of course repeated upon each tooth it is desired to set.

What is claimed is:—

In a saw set, an upper jaw comprising a slotted sheath and an integral head disposed in advance of said sheath, a guide plate adjustably secured to said head, a lower sectional jaw pivotally connected to said upper jaw, a spring disposed between said jaws, an adjustable saddle disposed 85 about said sheath and operatively connected to the same and to the lower sectional jaw and an adjustable anvil carried by the said lower sectional jaw.

In testimony that I claim the foregoing 90 as my own I have hereto affixed my signature in the presence of two subscribing witnesses.

ERIK W. SETTERLUND.
